UNITED STATES PATENT OFFICE

100,025

DESIGN FOR A PAPER PAIL OR THE LIKE

Tinsley T. Jepson, Neenah, Wis., assignor to Marathon Paper Mills Company, Rothschild,
Wis., a corporation of Wisconsin

Application April 23, 1936, Serial No. 62,261

Term of patent 7 years

To all whom it may concern:

Be it known that I, Tinsley T. Jepson, a citizen of the United States, residing at Neenah, in the county of Winnebago and State of Wisconsin, have invented a new, original, and ornamental Design for a Paper Pail or the Like, of which the following is a specification, reference being had to the accompanying drawing, forming a part thereof.

I claim:

The ornamental design for a paper pail or the like, as shown and described.

In testimony whereof I affix my signature.

TINSLEY T. JEPSON.
